OR D 19,595

UNITED STATES PATENT OFFICE.

CHARLES EDWARD HAVILAND, OF LIMOGES, FRANCE.

DESIGN FOR A DISH.

SPECIFICATION forming part of Design No. 19,595, dated January 21, 1890.

Application filed December 26, 1889. Serial No. 335,031. Term of patent 14 years.

To all whom it may concern:

Be it known that I, CHARLES EDWARD HAVILAND, a citizen of the United States, residing at Limoges, in the Republic of France, 5 have invented and produced a certain new and original Design for Dishes of a Table-Service, fully described and represented in the following specification and the accompanying drawings, forming a part of the same.

10 The leading or distinguishing characteristic of this design is the surface ornamentation of a deep dish, which is fully represented in the accompanying illustrations, in which—

15 Figures 1 and 2 are side views of a tea-cup embodying said design.

As shown in said figures, the deep dish is a

cup, which is of substantially equal diameter throughout its depth. It may or may not, as desired, be provided with a handle 1. The cup is encircled by two bands of ornamental 20 design 2, 3, 4, 5, and 6, and 7, 8, and 9, formed on the cup in intaglio or bas relief.

What I claim is—

The design for a deep dish, substantially as shown and described.

In testimony whereof I have hereunto set my hand in the presence of two subscribing witnesses.

CHARLES EDWARD HAVILAND.

Witnesses:

ALBERT HAVILAND,
GASTON LONGEVIAL.
